UNITED STATES PATENT OFFICE.

PHILIP W. MOORE, OF HUBBARD WOODS, ILLINOIS, ASSIGNOR TO THE P & M COMPANY, OF CHICAGO, ILLINOIS, A CORPORATION OF ILLINOIS.

RAIL ANCHOR.

Application filed April 24, 1926. Serial No. 104,356.

This invention relates to devices for resisting the longitudinal creeping movement of railroad rails.

The principal object of the invention is to provide a rail anchor of one-piece construction, which may be formed from a substantially rectangular blank of flat metal without loss of material, and which is of such configuration as to provide a relatively wide jaw at one end of the device, a spring jaw at the other end, and an angular body portion having a relatively wide bearing face for engagement with a cross tie.

Another object is to provide an improved rail anchor device of the above character, in which the blank, from which the device is formed, is bent intermediate its ends along a diagonal line to provide a self-bracing body portion, whereby the anchor may be made of relatively thin material and at the same time provide the necessary rigidity for resisting the stresses to which devices of this character are subjected.

The invention has for further objects the new and improved constructions hereinafter described and claimed for carrying out the above stated objects and such other objects as will appear from the following specification.

The invention is illustrated in two specific embodiments in the accompanying drawings, wherein:

Fig. 1 is a plan view of the base portion of a railroad rail showing a rail anchor device constructed in accordance with my invention applied thereto in its operative position.

Fig. 2 is a cross section through the base of a rail showing the device of my invention in side elevation, applied to the rail.

Fig. 3 is an end view of the rail anchor device shown in Figs. 1 and 2.

Fig. 4 is a view in perspective of the rail anchor device shown in the preceding figures.

Fig. 5 is a view of the metal blank from which the rail anchor shown in the preceding figures is formed; this view of the blank is made on a somewhat smaller scale than the preceding figures and is provided with dotted lines showing the lines along which the blank is bent to form the device shown in Fig. 4.

Fig. 6 is a view similar to Fig. 1 but show-

ing a modified form of anchor applied to the rail base, and

Fig. 7 is a view in perspective of the base portion of a railroad rail showing the modified form of anchor of Fig. 6, applied to the rail base.

Referring first to Figs. 1 to 5 inclusive of the drawings, 10 designates the base portion of a railroad rail, and 11 designates one embodiment of the invention applied in its operative position on the rail.

The embodiment of the invention shown in Figs. 1 to 4 inclusive consists of a rail base embracing yoke, formed at one end with a relatively wide jaw 12 which fits over one edge of the rail base, an angular body portion 13 which extends across beneath the rail base, and a resilient arm 14 at the other end of the device. The resilient arm 14 preferably extends longitudinally of the rail in a direction away from the adjacent cross tie and is formed at its extremity with a jaw portion 15 which fits over the adjacent edge of the rail base. The distance between the jaw 12 and the arm 14 is such that when the jaw 12 is fitted over one edge of the rail base, the arm 14 has to be flexed outwardly to clear the other edge of the rail base. The resiliency of the arm, when in engagement with the rail base draws the wide jaw 12 into firm gripping engagement with the rail base.

The above embodiment of the invention is formed from the substantially rectangular blank shown in Fig. 5 of the drawings. The angular body portion of the anchor is formed by bending the blank along the diagonal line 16. This bending of the blank moves the flat end portions to substantially right angles with respect to each other, and provides the middle portion with the angularly disposed flanges 17 and 18, one flange of which diminishes in width toward one end of the device and the other diminishes in width toward the other end. The angularly disposed flanges just described constitute the body portion of the anchor. The flange 17 bears edgewise against the under surface of the rail base and provides a relatively wide tie engaging face 19. The flange 18 extends laterally from the first mentioned flange, so as to rigidify the body portion. The flat end of the lateral flange 18 corresponds to the end 20 of the blank. This end

of the blank is preferably sheared so as to provide a diagonal edge 21 and the end is bent along lines 22 and 23 parallel to the diagonal edge so as to form the jaw portion 12 of the anchor. The jaw, it will be seen, corresponds in width to the full width of the blank and bears against the upper and vertical surfaces of the rail base. The other end of the blank is bent on the line 24 to provide the resilient arm 14. This arm, when bent to the position shown in Figs. 1 to 4 inclusive, stands edgewise with respect to the bottom surface of the base, extends longitudinally of the rail in a direction away from the cross tie, and normally stands at an acute angle with respect to the edge of the rail base when in its operative position. The upper and lower corners 25—26 of the arm are bent along lines 27 and 28 so as to form the jaw portion 15 at the extremity of the resilient arm.

In applying the device to a rail, the jaw 12 is first hooked over one edge of the rail base 10 with the face 19 of the body portion bearing against a cross tie. The jaw 12 may be forced to its rail gripping position by striking the applied end of the yoke with a suitable implement. When driving the jaw 12 to its gripping position, it is flexed in a vertical plane that is at a right angle to the length of the rail. In this initial position of the anchor, the extremity of the spring arm 14 remains under the base of the rail. The arm 14 is then flexed outwardly with respect to the edge of the rail base in a horizontal plane that is parallel to the longitudinal axis of the rail. When the flange 25 of the jaw portion 15 clears the edge of the rail, the extremity of the arm may be raised so as to permit the jaw to snap over the edge of the rail base to the applied position shown in Figs. 1 to 3 inclusive.

The resiliency of the arm 14 is preferably such as to exert a firm spring grip of the device transversely of the rail base, and the configuration of the body is such as to provide a relatively large tie engaging surface adjacent the spring arm of the anchor.

In the embodiment shown in Figs. 6 and 7, the spring arm 14^a instead of having its corners bent over to form a jaw, is provided with a recess 29 which receives the edge of the rail base. The arm is formed with a relatively sharp return bend so that the extremity 30 of the arm will engage the adjacent edge of the rail base at a point between the forward and rear edges of the jaw 12^a engaging the other edge of the rail base. With this arrangement of the spring arm 14^a, any turning movement of the anchor about a vertical axis, such as may result from the shifting of the tie to such position that the anchor bears at one end only against the tie, effects a firm shackle hold on opposite edges of the rail base. The modified embodiment

corresponds in other respects to the embodiment shown in Figs. 1 to 4 inclusive and is applied to its operative position on the rail in the same manner as that previously described.

While I have illustrated my invention in connection with two specific embodiments, it will be obvious to those experienced in this art, that various changes in form and construction may be made without departure from the spirit of the invention. It will therefore be understood that the invention contemplates all the modifications that come within the scope of the appended claims.

I claim:

1. A rail anchor consisting of a metal bar formed at opposite ends with rail base engaging jaws and bent intermediate said jaws along a diagonal line to provide an angular body portion.

2. A rail anchor consisting of a flat bar of metal, the middle portion and one end of which are disposed edgewise with relation to the rail base, and the other end of which bears flatwise against the rail base.

3. A rail anchor consisting of a metal bar, the end portions of which are disposed at substantially right angles to each other and formed with rail base engaging jaws adapted to grip opposite edges of a rail base, the said bar being bent intermediate said jaws to provide a vertically disposed web and a laterally disposed web.

4. A rail anchor consisting of a flat metal bar bent over at one end to provide a jaw adapted to bear flatwise against the rail base, the other end of the bar and the intermediate portion thereof being bent so as to stand edgewise with respect to the rail.

5. A rail anchor consisting of a flat metal bar bent over at one end to provide a jaw adapted to bear flatwise against the rail base, and formed intermediate the ends of the bar with a diagonal bend to provide a vertically disposed end portion, said vertically disposed end portions being bent to provide a spring arm adapted to be flexed outwardly with respect to the rail base in applying the anchor to the rail.

6. A rail anchor consisting of a flat metal bar bent along a diagonal line intermediate its ends to provide an angular body portion, one of the ends of the bar being formed with a jaw for engaging one edge of the rail base and the other end being bent to provide a resilient arm adapted to exert spring pressure against the opposite edge of the rail base.

7. A rail anchor consisting of a flat metal bar bent along a diagonal line intermediate its ends to provide an angular body portion, formed at one end with a jaw for engaging one edge of a rail base, and formed at the other end with a resilient arm, the extremity of which is provided with a recess adapted

to receive the outward edge of the rail base; said arm and jaw being arranged so that when the jaw is hooked over one edge of the rail base, the arm has to be flexed outwardly 5 with respect to the other edge of the rail base, to be moved into engagement with said rail base.

8. A rail anchor consisting of a flat metal bar bent along a diagonal line intermediate 10 its ends to provide an angular body portion, formed at one end with a jaw for engaging one edge of a rail base, and formed at the other end with a resilient arm, the extremity of which is bent over at the upper and lower 15 corners to provide a recess adapted to receive the opposite edge of the rail base; said arm and jaw being arranged so that when the jaw is hooked over one edge of the rail base the said arm has to be flexed outwardly with 20 respect to the other edge of the rail base in applying the anchor to its operative position on the rail.

9. A rail anchor consisting of a flat metal bar bent along a diagonal line intermediate 25 its ends to provide an angular body portion, formed at one end with a jaw for engaging one edge of the rail base and formed at the other end with a resilient arm which extends longitudinally of the rail and is provided 30 at its extremity with a recess adapted to receive the opposite edge of the rail base when the anchor is in its applied position.

10. A rail anchor consisting of a flat metal bar bent along a diagonal line intermediate 35 its ends to provide an angular body portion, provided at one end with a jaw for engaging the edge of a rail base and formed at the other end with a resilient arm which extends longitudinally of the rail and normally 40 stands at an acute angle with respect to the edge of the rail base and is provided at its extremity with a recess adapted to receive the adjacent edge of the rail base when the anchor is in its applied position on the rail.

11. A rail anchor consisting of a flat metal bar bent along a diagonal line intermediate 45 its ends to provide an angular body portion, bent at one end along lines parallel to the edge of the rail base with respect to the applied position of the anchor to provide a jaw 50 adapted to bear flatwise against the rail base, and formed at the other end with a resilient arm, the extremity of which is provided with a rail base receiving recess and is adapted to be flexed outwardly with respect to the adjacent edge of the rail in applying the anchor to the rail.

12. A rail anchor consisting of a flat metal bar bent along a diagonal line intermediate 55 its ends to provide a substantially vertically 60 disposed tie engaging flange and a flange extending laterally therefrom, formed at one end with a jaw for engaging one edge of the rail base, and formed at the other end with a resilient arm provided at its extremity 65

with a rail base receiving recess and adapted to be flexed outwardly with respect to the adjacent edge of the rail base in applying the anchor to the rail.

13. A rail anchor consisting of a flat metal 70 bar bent along a diagonal line intermediate its ends to provide a substantially vertically disposed tie engaging flange and a flange extending laterally therefrom, the said latter flange being bent to provide a jaw for engaging one flange of the rail base, and said vertically disposed flange being bent to provide a resilient arm adapted to be flexed outwardly with respect to the adjacent edge of the rail base to be moved into gripping engagement therewith.

14. A rail anchor consisting of a flat metal bar formed at opposite ends with rail base 75 gripping jaws and bent intermediate its ends along a diagonal line to provide a vertically disposed flange which diminishes in width toward one edge of the rail base and to provide a laterally disposed flange which diminishes in width toward the opposite edge of the rail base.

15. A rail anchor consisting of a flat metal bar formed at opposite ends with rail base 80 gripping jaws and bent intermediate its ends along a diagonal line to provide a vertically disposed flange which is of maximum width adjacent one edge of the rail base and diminishes in width toward the other edge thereof, and to provide a laterally disposed flange which diminishes in width toward the opposite edge of the rail base.

16. A rail anchor consisting of a flat metal bar formed at opposite ends with rail base 85 gripping jaws and bent intermediate its ends along a diagonal line to provide a vertically disposed flange which is of maximum width adjacent one edge of the rail base and diminishes in width toward the other edge thereof, and to provide a laterally disposed flange which diminishes in width toward the opposite edge of the rail base in proportion 90 to the increase in width of said vertically disposed flange.

17. A rail anchor consisting of a flat metal bar bent along a diagonal line intermediate 95 its ends to provide an angularly disposed body, formed at one end with a jaw for engaging one edge of a rail base, and formed at the other end with a return bend, the extremity of which is provided with a notch which fits over the other edge of the rail 100 base at a point intermediate the ends of said jaw.

18. A rail anchor consisting of a flat metal bar bent along a diagonal line intermediate 105 its ends to provide an angularly disposed body, formed at one end with a jaw for engaging one edge of a rail base, and formed at the other end with a relatively sharp return bend, the extremity of which is provided with a notch which fits over 110

the other edge of the rail base at a point intermediate the ends of said jaw.

19. A rail anchor consisting of a flat metal bar bent intermediate its ends along a diagonal line to provide a vertically disposed flange which diminishes in width toward one edge of the rail base, and to provide a laterally disposed flange which diminishes in width toward the opposite edge of said rail base, the wide end of said lateral flange being sheared along a diagonal line and bent on lines parallel to said shearing line to provide a jaw for engaging one edge of the rail base, and said vertical flange being bent to provide a spring arm, the extremity of which engages the opposite edge of the rail base with spring pressure.

20. A rail anchor consisting of a yoke member provided with jaw portions for engaging opposite edges of a rail base, one of said jaw portions being flexible in a vertical plane that is at right angles to the length of the rail and the other being flexible in a horizontal plane that is parallel to the longitudinal axis of the rail.

21. A rail anchor consisting of a metal bar bent intermediate its ends along a diagonal line to provide an angular body portion and provided at opposite ends with jaws for engaging opposite edges of the rail base, one of said jaws being flexible in a vertical plane that is at right angles to the length of the rail and the other being flexible in a horizontal plane that is parallel to the longitudinal axis of the rail.

22. A rail anchor consisting of a metal bar formed at opposite ends with rail base engaging jaws and bent intermediate said jaws to provide a vertically disposed web and a laterally disposed web; one of said jaws being flexible in a vertical plane that is at right angles to the length of the rail and the other being flexible in a horizontal plane that is parallel to the longitudinal axis of the rail.

23. A rail anchor consisting of a flat metal bar bent along a diagonal line intermediate its ends to provide a substantially vertically disposed tie engaging flange and a flange extending laterally therefrom, formed

at one end with a jaw for engaging the edge of the rail base and formed at the other end with a resilient arm provided at its extremity with a rail base receiving recess; said jaw being flexible in a vertical plane that is at right angles to the length of the rail and the resilient arm being flexible in a horizontal plane that is parallel to the longitudinal axis of the rail.

24. A rail anchor consisting of a flat metal bar bent along a diagonal line intermediate its ends to provide an angular body portion, one of the ends of the bar being formed with a jaw for engaging one edge of the rail base and the other end being bent to provide a resilient arm adapted to exert spring pressure against the opposite edge of the rail base; the normal position of said arm with respect to said jaw when the anchor is free of the rail, being such that after hooking said jaw over one edge of the rail base it is necessary to move the said arm outwardly and upwardly to its rail gripping position.

25. A rail anchor consisting of a flat metal bar bent along a diagonal line intermediate its ends to provide an angular body portion, one of the ends of the bar being formed with a jaw for engaging one edge of the rail base and the other end being bent to provide a resilient arm which extends in a direction so away from the adjacent cross tie and is adapted to exert spring pressure against the edge of the rail base.

26. A rail anchor consisting of a flat bar of spring metal bent along a diagonal line intermediate its ends to provide an angular body portion, one of the ends of the bar being formed with a jaw portion for engaging one edge of the rail base and the other end being bent to provide an arm which extends longitudinally of the rail in a direction away from the adjacent cross tie; the position of said arm with respect to said jaw being normally such when the device is free of the rail that it is necessary to force said arm outwardly and move the same upwardly into engagement with the edge of the rail base, in applying the anchor to a rail.

PHILIP W. MOORE.
